DESIGN FOR A BOTTLE

Charles S. Gage, Tarrytown, N. Y., and Wilbur D. Canaday, Stamford, Conn., assignors to Lentheric Incorporated, New York, N. Y., a corporation of New York

Application December 22, 1933, Serial No. 50,184

Term of patent 14 years

To all whom it may concern:

Be it known that we, Charles S. Gage, a citizen of the United States, residing at 300 South Broadway, Tarrytown, New York, and Wilbur D. Canaday, a citizen of the United States, residing at 162 Fifth Street, Stamford, Connecticut, have invented a new, original, and ornamental Design for a Bottle, of which the following is a specification, reference being had to the accompanying drawing, forming a part thereof.

In the drawing:

We claim:

The ornamental design for a bottle substantially as shown.

CHARLES S. GAGE,
WILBUR D. CANADAY.
